(57) **CLAIM**

The ornamental design for a leak resistant dropper, as shown and described.

DESCRIPTION

FIG. 1 illustrates a top perspective view of a leak resistant dropper.

FIG. 2 illustrates a front view of the leak resistant dropper illustrated in FIG. 1.

FIG. 3 illustrates a back view of the leak resistant dropper illustrated in FIG. 1.

FIG. 4 illustrates a side view of the leak resistant dropper illustrated in FIG. 1.

FIG. 5 illustrates another side view of the leak resistant dropper illustrated in FIG. 1.

FIG. 6 illustrates a top view of the leak resistant dropper illustrated in FIG. 1.

FIG. 7 illustrates a bottom view of the leak resistant dropper illustrated in FIG. 1.

FIG. 8 illustrates a bottom perspective view of the leak resistant dropper illustrated in FIG. 1.

FIG. 9 illustrates a cross-sectional view, taken from the direction of arrows 9-9 in FIG. 2, of the leak resistant dropper illustrated in FIG. 1.

FIG. 10 illustrates a top perspective view of the leak resistant dropper illustrated in FIG. 1, shown with an unclaimed environment of a skirt. The dropper and the unclaimed skirt form a cap.

FIG. 11 illustrates a front view of the leak resistant dropper illustrated in FIG. 10.

FIG. 12 illustrates a back view of the leak resistant dropper illustrated in FIG. 10.

FIG. 13 illustrates a side view of the leak resistant dropper illustrated in FIG. 10.

FIG. 14 illustrates another side view of the leak resistant dropper illustrated in FIG. 10.

FIG. 15 illustrates a top view of the leak resistant dropper illustrated in FIG. 10.

FIG. 16 illustrates a bottom view of the leak resistant dropper illustrated in FIG. 10.

FIG. 17 illustrates a bottom perspective view of the leak resistant dropper illustrated in FIG. 10.

FIG. 18 illustrates a cross-sectional view, taken from the direction of arrows 18-18 in FIG. 11, of the leak resistant dropper illustrated in FIG. 10.

(Continued)

FIG. 19 illustrates a top perspective view of the leak resistant dropper illustrated in FIG. 1, shown with unclaimed environment of a skirt and a bottle. The dropper and the unclaimed skirt form a cap of the unclaimed bottle. FIG. 20 illustrates a front view of the leak resistant dropper illustrated in FIG. 19. FIG. 21 illustrates a back view of the leak resistant dropper illustrated in FIG. 19. FIG. 22 illustrates a side view of the leak resistant dropper illustrated in FIG. 19. FIG. 23 illustrates another side view of the leak resistant dropper illustrated in FIG. 19. FIG. 24 illustrates a top view of the leak resistant dropper illustrated in FIG. 19. FIG. 25 illustrates a bottom view of the leak resistant dropper illustrated in FIG. 19. FIG. 26 illustrates a bottom perspective view of leak resistant dropper illustrated in FIG. 19. FIG. 27 illustrates a cross-sectional view, taken from the direction of arrows 27-27 in FIG. 20, of the leak resistant dropper illustrated in FIG. 19; and, FIG. 28 illustrates a side view of the leak resistant dropper illustrated in FIG. 1 shown in an unclaimed environment of a bottle. The dropper is a cap in the unclaimed bottle. The broken lines and unshaded surfaces depicting parts of the dropper bulb, flange, and pipette show parts of the leak resistant dropper that form no part of the claimed design. The broken lines depicting a skirt and bottle in FIGS. 10-28 show environmental subject matter only and form no part of the claimed design.
